CLAIM

The ornamental design for a control console, as shown and described.

DESCRIPTION

FIG. 1 is a top, front right side perspective view of a control console showing our new design;

FIG. 2 is a left side elevational view thereof, the right side being a mirror image;

FIG. 3 is a rear elevational view thereof; and,

FIG. 4 is a bottom plan view thereof.

The broken line showing of control panel features and grilles is for illustrative purposes only and forms no part of the claimed design.
